CLAIM

The ornamental design for a bracket for securing tall yard decorations, as shown and described.

DESCRIPTION

FIG. 1 is an isometric view of the bracket for securing tall yard decorations;

FIG. 2 is a front elevational view of FIG. 1;

FIG. 3 is a rear plan view of FIG. 1;

FIG. 4 is a right elevational view of FIG. 1;

FIG. 5 is a left elevational view of FIG. 1;

FIG. 6 is a top plan view of FIG. 1;

FIG. 7 is a bottom plan view of FIG. 1;

FIG. 8 is an exploded view of FIG. 1;

FIG. 9 is the bracket for securing tall yard decorations of FIG. 1, shown in a position of use; and,

FIG. 10 is the bracket for securing tall yard decorations of FIG. 1, shown in another position of use.

The broken lines shown in the FIGS. 9 and 10 illustrate portions of the environment of the bracket for securing tall yard decorations and form no part of the claimed design.

The stippling in FIGS. 1-8 shows contrast in appearance.
